(57) **CLAIM**

The ornamental design for a driving recorder, as shown and described.

DESCRIPTION

FIG. 1 is a top, rear and left side perspective view of a driving recorder showing my new design;

FIG. 2 is a bottom, front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2; and,

FIG. 10 is an enlarged view of portion 10 shown in FIG. 3.

The broken lines depict portions of the driving recorder in which the design is embodied that form no part of the claimed design. Additionally, the dot-dash broken lines encircling an enlargement portion of the design form no part of the claimed design.
